NOISELESS TYPEWRITER

Harry Bates, New York, N. Y., assignor to Bates Laboratories, Inc., New York, N. Y., a corporation of New York

Application June 16, 1934, Serial No. 730,902

28 Claims. (Cl. 197—25)

The invention relates to a functionally and structurally improved noiseless operating typewriter having type bars selectively responsive to a staccato touch applied to a respective key, the typewriter being characterized by relatively fast operating type bars actuated by a relatively soft pressure on selected keys. In certain aspects, the invention has to do with a noiseless typewriter having means for carrying into effect uniform typing independent of the character of the touch applied to the keys. In other aspects, the invention comprises a typewriter having a multiplicity of keys each operatively associated with a respective type bar each of which effectively and uniformly prints pursuant to the removal of finger pressure on a selected key. In other aspects, the invention has to do with means for advancing in a relatively fast fashion the type bars towards and against the platen in several stages. More specifically, as another aspect, the invention embodies means for interrupting or stopping the swing of a type bar for a relatively short duration preparatory to its reaching the platen, the interrupting means being in the form of a toggle pivotally connected to the type bar, the toggle having a shiftable pivotal connection and permitting on the upward displacement thereof, the type bar to move in close spatial relation to the platen after which the shiftable pivotal connection is automatically actuated to change the pivotal relation of the toggle in respect to the type bar to permit the toggle during its downward displacement to advance the type bar against the platen in carrying into effect the printing operation following which the pivotal relation of the toggle in respect to the type bar is again automatically changed.

In the accompanying specification I shall describe and in the annexed drawing more or less diagrammatically exemplify an illustrative embodiment of the present invention, particularly in respect to its cycle of operation, although it is to be clearly understood that the invention is not limited to the specific embodiment herein shown and described for purposes of illustration only and in said drawing:—

Fig. 1 is a fragmentary transverse view partly in section of a noiseless typewriter according to my invention, illustrating a type bar in a normally non-printing position and at rest and the toggle collapsed.

Fig. 2 is a view showing the position of a type bar after its respective key lever has been struck, particularly illustrating the toggle expanded, with clamping component thereof about to compress a stationary spring and its companion complement passing upwardly through the zone of dead center.

Fig. 3 illustrates the clamping component of the toggle compressing the stationary spring and

its companion component past the zone of dead center preparatory to the completion of the printing stroke by the type bar.

Fig. 4 illustrates the spring released having urged the clamping complement of the toggle 5 downwardly, the companion complement passing downwardly through the zone of dead center at which time the type bar carries into effect the printing operation and

Fig. 5 is an exploded fragmentary view in perspective of the control mechanism for automatically shifting a respective displaceable pivot about which the components of the toggle swing.

The typewriter, according to the invention, is generally designated 10 and comprises keys or 15 key levers as 11 for actuating individual control mechanism, broadly denoted 12, to operate a respective type bar 13. As shown, only one key lever with its control mechanism for operating a respective type bar has been illustrated. In 20 actual practice, a plurality of sets of keys or key levers are provided, each lever operating its respective control mechanism and its control mechanism operating an associated type bar, the group of control mechanism and respective type 25 bars being arranged in conventional segmental fashion as is well understood.

Each control mechanism comprises a tie rod 14; a toggle generally indicated 15 and operatively associated pivoted links 16 and 17. The rod 14 30 appropriately interconnects the clamping complement 18 of toggle 15 with a respective key lever 11. Toggle 15 serves to interrupt or stop the swing of a respective type bar and comprises a bell crank shaped clamping complement 18 and 35 an associated displaceable companion complement 19, the inner ends of the complements being pivotally interconnected in overlapping relation by means of a suitable rivet or post 20. Complement 19 has its outer end appropriately pivotally 40 connected to an intermediate portion of the type bar 13 which has its lower end pivoted on a fixed rod 21.

The clamping complement 18 is provided with a floating and displaceable pivotal connection; 45 that is, during the cycle of operation, its fulcrum post 22, at times, is pivotally disposed at the upper part of the irregularly shaped cam slot 23 (Figs. 1 and 2) of the swingable and pivoted link 16 and at other times is pivotally arranged 50 at the lower part of the cam slot 23 (Figs. 3 and 4).

The link 17 is pivotally mounted on the fixed post 24 and its upper portion rotatably carries the cylindrical stud 22 which projects into and 55 beyond the cam slot 23 of link 16 having its upper end pivotally mounted on the fixed post 25. Fulcrum pin or stud 22 also frictionally extends into perforation 26 of the clamping portion 27 of component 18 and has its free end slightly upset to 60

prevent lateral displacement of component 18 relative to links 16 and 17, that is to say, stud 22 is bodily movable with the bell crank complement 18, having one end appropriately journaled or secured to link 17, the pin 22 being adapted to be displaced by the action of the cam faces of slot 23 as is well understood.

The clamping head 27 of complement 18 is provided with a cam or nose shaped element 28 having an upper curved face 29 and a lower rectilinear face 30. Cam 28 has a double function; one to collapse a respective stationary relatively heavy duty U shaped spring, generally designated 31, in the upward displacement of the toggle and two, to abut post 32 carried by locking link 16 on the downward displacement of the clamping component 18, to shift the floating pivot, that is, the displaceable pin 22 from its position at the lowermost part of cam slot 23 to the uppermost part of this slot and consequently changing pivotal relation of the toggle 15 in respect to an associated type bar. The clamping head 27 also embodies a projection 33 which cooperates with post 32 of link 16, to raise the latter and shift the displaceable fulcrum post 22 from its uppermost part of the cam slot 23 to the lowermost part thereof where it is locked and pivotally sustained until such time that the spring 31 releases its energy forcing cam 28 downwardly whereby rectilinear cam face 30 strikes abutment post 32, consequently raising the displaceable pivot pin 22, thereby restoring the initial pivotal relation of the toggle in respect to the type bar.

Each spring as 31 has its upper leg immovably mounted and its lower leg adapted to be displaced inwardly or collapsed, there being a cushioning instrumentality 34 appropriately interposed between the legs to eliminate clicking and undesirable noises during the coaction of cam 28 with spring 31. In Fig. 1, cam 28 is away from the free lower leg of the U shaped spring. In Fig. 2, cam 28 has just contacted the lower leg of this spring. In Fig. 3, the free leg of spring 31 is shown collapsed and urged against the cushioning instrumentality 34. In Fig. 4, the free leg of spring 31 has released its energy, being again expanded, having transmitted its energy to the head or clamping portion 27 of complement 18 whereby the inner end of the latter is caused to be moved downwardly.

Assuming a key 11 is in a normally raised position, as indicated by the full lines in Fig. 1, that is, its respective toggle is collapsed and its associated type bar 13 at rest and in a position furthest away from the cooperative cylindrical platen 35 and it is desired to render type bar 13 effective for casting an impression against the platen the operator applies a staccato touch to a key 11, causing the body of the latter to be displaced downwardly about its fulcrum 36 consequently expanding the associated relatively light weight helicoidal spring 37 which normally maintains the manipulating portion of a key lever in a desired raised position.

Displacement of an operated key in a downward direction, causes an associated rod 14 to be correspondingly displaced, thus readily raising component 18 of toggle 15 and the curved face 29 of cam 28 contacts the free lower leg of spring 31. The toggle, however, has moved upwardly and its companion complement or link 19 is substantially horizontal, or passing through the zone of dead center, that is, although the toggle continues to travel upwardly, its associated type 13 does not move towards the platen. In other

words, movement of the type bar has been interrupted or stopped until the zone of dead center is passed. Consequently, the type bar stops or hesitates momentarily, losing all of its momentum. Complement 18, however, passes the dead center and the inner portions of the toggle continue to move upwardly, hence cam 28 causes the free leg of spring 31 to be displaced against the cushioning instrumentality 34.

Projection 33 has also come into contact with 10 the abutment post 32, thereby raising locking link 16, which action by reason of cam slot 22 causes the displaceable fulcrum stud or pin 22, to shift inwardly and downwardly and accordingly occupy the lowermost position of the cam slot 23. 15 Although pivot pin 22 has been displaced and the spring is compressed (Fig. 3), type bar 13, however, has not struck the platen, being slightly spaced therefrom. By this time, the operator has removed finger pressure from the key. Thus 20 it is apparent, that although a key has been struck, nevertheless, no printing has been effected.

In accordance with the invention, printing of any character is made during downward displacement of the toggle pursuant to the expansion of the associated U shaped spring and only 25 after the pivotal relation of the clamping component of the toggle has been changed.

The energy stored up in spring 31 automatically 30 causes downward displacement of the inner parts of the toggle, that is, the free leg of spring 31 tends to expand or "kick back" driving cam 28 downwardly. This action causes the clamping head 27 to rotate about its new pivotal position, 35 namely fulcrum pin 22 being now removably locked and pivotally sustained at the bottom of cam slot 23. Consequently, the inner ends of the toggle move downwardly causing the displacement or advancement of the type bar 13 towards the platen and against the latter until complement 19 has passed the zone of dead center, and during the travel of complement 19 through the zone of dead center the operated type bar cast a uniform impression against the platen. 40

Having passed the zone of dead center on the return or downward stroke of the toggle, the latter causes the type bar to recede from the platen and the rectilinear face 30 of cam 28 abuts post 32, thus moving locking link 16 downwardly 50 which action causes the displaceable pivotal connection for the toggle again to shift; in this instance, the displaceable fulcrum post 22 automatically is restored to the upper part of the cam slot 23 where it is removably locked and pivotally 55 sustained until such time that another staccato touch is applied to a respective key.

With the present arrangement, as previously pointed out, printing is effected only after a key 60 has been released from finger pressure on the part of the operator. This is an important feature of the invention. The automatic changing of the pivotal relation of a toggle in respect to an operatively associated type bar is another important feature of the invention.

In carrying the invention into effect, each control mechanism is provided with a U shaped spring having a desired pressure. The release of an associated U shaped spring causes a respective type bar to print. Hence uniform printing is obtained. This is another important feature of the invention. By reason of the action of the U shaped springs in shifting respective cam 28 downwardly, associated tie rods and keys accordingly will be raised, thus supplementing the action 75

of a respective helicoidal spring 37. Accordingly relatively light weight springs as 37 may be employed.

If desired, platen 35 may be moved bodily towards or away from the normal rest position (Fig. 1) of the type bars by any suitable means, a predetermined distance and subsequently locked in a selected set position. In this way, a convenient method is had for adjusting the swingable stroke of the keys to suit the touch of the operator.

Many modifications of the invention will be apparent to those skilled in the art without departing therefrom or from the scope of the claims and since the foregoing disclosure has been given by way of example for clearness and understanding, no unnecessary limitations should be understood and the appended claims should be construed as broadly as the state of the art permits.

20 I claim:

1. In a typewriter, the combination of, key means, means actuated by said key means for advancing a type bar within close proximity to a platen, and spring means acting against said actuated means for moving said type bar against said platen and away therefrom.

2. In a typewriter, the combination of, key means, means actuated by said key means on a downward stroke thereof for advancing a type bar towards and in close spatial relation to a platen, and spring means operating against said actuated means for moving said type bar against said platen and away therefrom during upward displacement of said key means.

3. In a typewriter, the combination of, depressible key means, means actuated by said key means on a downward stroke thereof for advancing a type bar towards and in close spatial proximity to a platen, said actuated means having a predetermined pivotal relation in respect to said bar, displaceable means for changing said relation, spring means acting against said actuated means for moving said type bar against said platen and away therefrom during upward displacement of said key means, said actuated means having means for restoring said predetermined pivotal relation on said upward displacement.

4. In a typewriter, the combination of, a platen, depressible key means, control means operatively connected to said key means, type means displaceable in response to the actuation of said control means and operatively associated therewith, said type means adapted to be advanced within close proximity to said platen upon the application of pressure on said key means, and means operative subsequent to the removal of said pressure for moving said type means against said platen during retraction of said key means.

60 5. In a typewriter, the combination of, a platen, key means, control means operatively connected to said key means, type means displaceable in response to the actuation of said control means and operatively associated therewith, said control means having means to initially advance and stop said type means within close proximity to said platen upon the application of pressure on said key means, and means operative subsequent to the removal of said pressure for moving said type means against said platen and away therefrom.

65 6. In a typewriter, the combination of, a platen, depressible key means, control means operatively connected to said key means, type means swingable in response to the actuation of said control means and operatively associated therewith, said

control means operating to advance and stop said type means within close proximity to said platen upon the application of pressure on said key means, and spring means acting against said control means and operative subsequent to the removal of said pressure for moving said type means against said platen and away therefrom

7. In a typewriter, the combination of, a platen, depressible key means, control means operatively connected to said key means and comprising a toggle having a shiftable pivotal connection, a type bar operatively associated with said toggle and spring means common to said control and key means, said toggle on the downward displacement of said key means advancing said type bar within close proximity to said platen, said spring means acting against said toggle to urge adjacent intermediate portions thereof downwardly to shift said type bar against said platen and subsequently away therefrom, said control means having means for displacing said pivotal connection to change the initial pivotal relation of said toggle in respect to said type bar on the downward displacement of said key means, said control means having means to restore said initial pivotal relation on the downward displacement of said toggle.

8. In a typewriter, the combination of, a platen, depressible key means, control means operatively connected to said key means and comprising a toggle, a type bar pivotally associated with said toggle, spring means, said control means having means upon the application of pressure on said key means for swinging an intermediate portion of said toggle upwardly to dispose said type bar adjacent said platen and to compress said spring means, said control means comprising a displaceable member for shifting the pivotal relation of said toggle in respect to said bar, said spring means pursuant to the removal of said pressure acting against said toggle to urge intermediate portions thereof downwardly and move said type bar against said platen and away therefrom.

9. In a typewriter, the combination of, a platen, depressible key means, control means operatively connected to said key means and comprising a toggle, a type bar pivotally associated with said toggle, a relatively heavy duty spring disposed adjacent said toggle, said control means having means upon the application of pressure on said key means for moving intermediate portions thereof upwardly to dispose said type bar adjacent said platen and to compress said spring, said control means comprising a pivotal and displaceable member for shifting the pivotal relation of said toggle means in respect to said type bar, said spring pursuant to the removal of said pressure acting against said toggle to urge adjacent portions thereof downwardly and move said type bar against said platen and away therefrom.

10. In a typewriter, the combination of, a platen, depressible key means, control means operatively connected to said key means and comprising toggle means, a type bar pivotally associated with said toggle means, a relatively heavy duty spring disposed adjacent said toggle, said control means having means upon the application of pressure on said key means for moving said type bar adjacent said platen and to compress said spring, said control means comprising a pivotal and displaceable member for shifting the initial pivotal relation of said toggle means in respect to said type bar, said spring pursuant to the removal of said pressure acting against said toggle to move said type bar against said

platen and away therefrom, said control means having means restoring said initial pivotal relation.

11. In a typewriter, the combination of, de-
5 pressible key means, means actuated by said key means upon application of pressure thereon for advancing a type bar towards and in close spatial proximity to a platen, said actuated means having a predetermined pivotal relation in re-
10 spect to said bar, displaceable means operatively connected to said actuated means for shifting the said predetermined relation pursuant to the advancement of said bar within said close spatial relation and spring means operating said actuated means for moving said type bar against said platen and away therefrom pursuant to the removal of said pressure, said displaceable means having means operated by said actuated means for restoring said predetermined pivotal relation
20 pursuant to the retraction of the type bar from said platen and a relatively light weight resilient member operatively connected to said key means to resist downward displacement thereof.

12. In a typewriter, the combination of, a
25 platen, pivoted key means, a pivoted member including a fulcrum pin, a pivotal locking member having an irregularly shaped opening surrounding said pin, a clamping element secured to said pin and comprising cam means, a type bar, a link
30 pivotally connected to a portion of said clamping element and said type bar, a spring, means inter-
connecting said clamping element and said key means to actuate said clamping element for advanc-
35 ing said type bar in close proximity to and in spaced relation with said platen upon the application of pressure on said key means and for compressing said spring, a projection on said locking member, said clamping element having means for abutting said projection for shifting
40 said fulcrum pin to a lower portion of said opening.

13. In a typewriter, the combination of, a
45 platen, pivoted key means, a pivotal member including a fulcrum pin, a pivoted locking member having an irregularly shaped opening surrounding said pin, a clamping element secured to said pin and comprising cam means, a type bar, a link
50 pivotally connected to a portion of said clamping element and said type bar, a spring, means inter-
connecting said clamping element and said key means to actuate said clamping element automatically for advancing said type bar in close proximity to but in spaced relation with said platen upon the application of pressure on said key means and for compressing said spring, a projection on said locking member, said clamping element having means to abut said projection for shifting said fulcrum pin to a lower portion of said opening, said spring upon the removal of
55 said pressure urging said cam downwardly to advance said type bar against said platen and away therefrom, said cam having means cooperating with said projection for displacing said locking member to arrange said fulcrum pin at the
60 upper part of said opening.

14. In a typewriter, the combination of, a
70 platen, pivoted depressible key means, a pivoted member including a fulcrum pin, a pivoted locking member having an irregularly shaped opening surrounding said pin, a pivoted clamping element secured to said pin and comprising cam means, a pivoted type bar, a link pivotally connected to a portion of said clamping element and said type bar, a spring, means interconnecting
75 said clamping element and said key means for

actuating said cam means to operate said element and advance and stop said type bar in close proximity to and in spaced relation with said platen upon the application of pressure on said key means and for compressing said spring, a projection on said locking member, said clamping element having means for abutting said projection for shifting said fulcrum pin longitudinally of said opening, the sides of said opening having means for pivotally retaining said pin. 10

15. In a typewriter, the combination of, a platen, pivoted key means, a pivoted member including a fulcrum pin, a pivoted locking member having an irregularly shaped elongated opening surrounding said pin, a clamping element secured to said pin and comprising a cam, a swing-
15 able type bar, a link pivotally connected to a portion of said clamping element and said type bar, a spring, means interconnecting said clamping element and said key means for elevating said cam and for actuating said element to advance said type bar in close proximity to and in spaced relation with said platen upon the application of pressure on said key means and for compressing said spring, a projection on said locking member, said clamping element having means for abutting said projection to shift said fulcrum pin longitudinally of said opening to one end thereof, said spring upon the removal of
20 said pressure urging said cam downwardly to advance said type bar against said platen, said cam having means cooperating with said projection for displacing said locking member downwardly to arrange said fulcrum pin at another end of said opening, the latter having cam faces to dis-
25 placeably retain and pivotally lock said pin at either of said ends. 30

16. In a typewriter, the combination of, a
40 platen, a type bar, a toggle operatively associated with said type bar, key means operatively connected to said toggle, means upon the application of pressure on said key means for expanding said toggle, a spring, said toggle having means for compressing said spring, and means for dis-
45 placeably retaining and pivotally locking a portion of said toggle. 50

17. In a typewriter, the combination of, a
55 platen, a type bar, a toggle operatively connected to said type bar, key means operatively connected to one end of said toggle, said end comprising cam means, a projection and a fulcrum pin; a pivoted link having one end carrying said pin, a pivoted locking element including an abutment and comprising an irregularly shaped cam slot surrounding said pin, said toggle in the upward displacement thereof causing said projection to strike said abutment for shifting said pin from an upper part of said slot to the lower part thereof, said cam means on the downward displacement of said toggle striking said abutment for raising said fulcrum pin from the lower part of said slot to an upper portion thereof. 60

18. In a typewriter, the combination of, a platen, key means, type means, control means for advancing and stopping said type means within close spatial proximity to said platen on the application of pressure on said key means, and automatic means for operating said control means to move said type means towards and against said platen and away therefrom upon the re-
70 moval of said pressure. 65

19. In a typewriter, the combination of, a platen, key means, type means, control means for advancing said type means towards said platen and for stopping said type means a predeter- 75

mined distance therefrom upon the application of a relatively light pressure on said key means, and means for automatically operating said control means to move said type means against said platen and subsequently away therefrom upon the removal of said pressure.

20. In a typewriter, the combination of, a platen, depressible key means, control means operatively connected to said key means and comprising a toggle, a type bar pivotally associated with said toggle, spring means, said control means having means upon the application of pressure on said key means for moving intermediate portions thereof through a zone of dead centre to dispose said type bar in close but spaced relation to said platen and to compress said spring means, said control means comprising a pivotal and displaceable connection for changing the pivotal relation of said toggle in respect to said type bar pursuant to the travel of said intermediate portions through said zone of dead centre, said spring means pursuant to the removal of said pressure cooperating to urge said intermediate portions downwardly and through said zone of dead centre and move said type bar against said platen and away therefrom, and means cooperating to change said pivotal relation of said toggle relative to said type bar during retraction of said key means.

30. 21. In a typewriter, the combination of, a platen, depressible key means, a type bar, a toggle comprising a shiftable pivotal connection and a link pivotally secured to said type bar, means operatively connecting said toggle and key means and actuated in response to the application of pressure on the latter to actuate said link means through a zone of dead centre to dispose said type bar in close spatial proximity to said platen and cause said toggle to break above the zone of dead centre, spring means actuated by said toggle, means for actuating said shiftable pivotal connection to change the pivotal relation of said toggle in respect to said type bar pursuant to the travel of said link through said zone of dead centre, said spring means upon the removal of said pressure acting on said toggle to move said link downwardly through said zone of dead centre to dispose said type bar against said platen and subsequently away therefrom to retract said type bar, and means pursuant to the travel of said link downwardly through said zone of dead centre for actuating said pivotal connection to again change the pivotal relation of said toggle in respect to said type bar.

55. 22. In a typewriter, the combination of, key means, a type bar, a platen, means actuated by said key means for advancing said type bar within close spatial proximity to said platen, said actuated means comprising a toggle having a shiftable pivotal connection and having intermediate portions adapted to pass through a zone of dead centre and break above said zone during the spaced relation of said type bar relative to said platen, and spring means acting against said platen and away therefrom.

70. 23. In a typewriter, the combination of, key means, a type bar, a platen, means actuated by said key means for advancing said type bar towards and in close spatial proximity to said platen, said actuated means comprising a toggle having intermediate portions adapted to pass through a zone of dead centre and break above said zone during the spaced relation of said type bar relative to said platen, said actuated means

having an initial predetermined pivotal connection shiftable pursuant to breaking of said toggle to change the initial pivotal relation of said toggle relative to said type bar, and spring means acting against said toggle to urge said intermediate portions thereof downwardly through said zone of dead centre and dispose said type bar against said platen and subsequently away therefrom, and means for actuating said pivotal connection to restore the initial pivotal relation of said type bar relative to said platen.

24. In a typewriter, the combination of a platen, a type bar, means for interrupting the swing of said type bar for a relatively short duration prior to its reaching said platen, said means comprising a toggle pivotally connected to said type bar and including a shiftable pivotal connection having a predetermined initial pivotal relation in respect to said type bar, means for displacing said connection pursuant to the interruption of said swing to change the initial pivotal relation and spring means acting against said toggle to urge said type bar against said platen and subsequently away therefrom and means for actuating said pivotal connection to restore said initial pivotal relation.

25. In a typewriter, the combination of a type bar, a platen, means for interrupting the swing of a type bar for a relatively short duration prior to its reaching said platen, said means comprising a toggle pivotally connected to said type bar and including a shiftable pivotal connection having a predetermined pivotal relation in respect to said type bar, said toggle having a portion adapted to break above the zone of dead centre pursuant to the interruption of said swing, spring means acting against said toggle to urge said type bar against said platen and away therefrom, and means for actuating said pivotal connection to restore said initial pivotal relation.

40. 26. In a typewriter, in combination, a platen, type means movable toward and away from the platen, key means, and means cooperating with said type means and key means for causing the latter to approach but not touch the platen upon depression of the key means and to move into contact with the platen upon release of pressure from the key means.

45. 27. In a typewriter, in combination, a platen, type means movable toward and away from the platen, key means, a toggle operatively connected to said type means and key means, shiftable pivot means for said toggle normally maintaining the toggle in such position that said type means upon application of pressure on said key means will be advanced within close proximity of the platen as the toggle rises from a lower position through a zone of dead center to an upper position, and means for shifting the toggle pivot means toward the platen to cause the toggle in descending from 60 its upper position to the lower position through said zone of dead center to move said type means against said platen.

55. 28. In a typewriter, in combination, a platen, type means movable toward and away from the platen, key means, means operatively connecting the type means and key means and including a toggle, shiftable pivot means for the toggle to cause the toggle to move toward or away from the platen, and means actuated by the toggle for shifting said pivot means toward the platen when the toggle is moved in one direction and for shifting said pivot means away from the platen when the toggle is moved in the opposite direction.
